UNITED STATES PATENT OFFICE.

JAMES H. McCLURE, OF MARTIN'S FERRY, OHIO.

BUTTON-FASTENER.

SPECIFICATION forming part of Letters Patent No. 281,899, dated July 24, 1883.

Application filed January 22, 1883. (No model.)

To all whom it may concern:

Be it known that I, JAMES H. McCLURE, of Martin's Ferry, in the county of Belmont and State of Ohio, have invented a new and useful Improvement in Shoe-Button Fastener; and I do hereby declare the following to be a full, clear, and exact description thereof, reference being had to the accompanying drawings, forming a part of this specification, in which—

10 My invention relates to the devices for fastening shoe-buttons in shoes. As the ordinary means of sewing these buttons on shoes is objectionable on account of the thread wearing out rapidly because of the strain thereon in the constant moving of the foot in walking, some permanent means for fastening these buttons whereby the wear or strain may come against a metal wire or loop which will not wear out so rapidly has been sought for. Among the 20 other devices for this purpose, a wire having a bent portion in the center has been employed, the eye of the button being inserted through a hole in the leather of the shoe and this wire passed through the eye, the bent portion catching the eye and holding it. These were, however, difficult to attach on account of the thickness of the leather and lining of the shoe, and the wire was liable to be bent and drawn through the hole by the strain on the button. 25

30 By my invention these objections are overcome. It consists, essentially, of a button-fastener formed of wire and having a base bent so as to give a strong hold against the inner side of the shoe-leather, and having in the center of this base a hook adapted to extend through the hole in the shoe-leather, and a spring-snap extending through said shoe and adapted to be pressed back on the outer surface of the shoe-leather, so as to permit the eye of the button 35 to enter the catch and be held by the hook thereof, the button being thus secured within the fastener above the shoe, and so being more readily secured in place and removed when desired, and being capable of removal without 40 removing the fastener from the shoe.

45 To enable others skilled in the art to make and use my invention, I will describe the same more fully, referring for that purpose to the accompanying drawings, in which—

50 Figure 1 is a perspective view of my improved fastener. Figs. 2 and 3 are views of the same extending through the leather of the

shoe, and having the button secured therein; and Fig. 4 is a view of another form of the same.

Like letters of reference indicate like parts 55 in each.

My improved shoe-fastener is formed of a single piece of wire of suitable size and strength, being bent to the desired shape by means of suitable tools or machinery. The ends of the 60 wire are cut off at an angle and one end thereof is bent in the form of a hook, *a*, the end cut off at an angle forming a lip to catch the spring-snap, as hereinafter described, and the wire then extending down, leaving a hook of 65 sufficient length to extend through the hole in the shoe-leather and support the shoe-button on the upper side thereof. At the base of this hook the wire is bent in any desired shape, so as to form a strong base, *b*, to fit against the 70 under surface of the leather and to sustain the drawing strain of the button thereon. After bending this base *b*, the other end of the wire is bent up in the center of the base, so as to fit under the lip of the hook *a* to form the spring- 75 snap *c*, the hook and the spring-snap both being adapted to extend through the hole in the shoe-leather, so that the eye of the button *d* can be pressed against this spring-snap *c*, and, pressing it back, enter within the fastener and 80 be held by the hook *a*.

The base *b* of the fastener may be made of any suitable shape to give the required strength thereto, it being shown in two forms in the drawings. The form preferred by me is that 85 shown in Fig. 1, in which the base has the form of an ellipse, being bent back of the hook and around to the front of it, and then up, to form the spring-snap. By this construction the fastener is constructed so that the spring-snap can be pressed back close to the hook and allow the button to enter the fastener easily. In the other form (shown in Fig. 3) the base *b* is bent substantially in the form of the letter 90 **S**, the wire of the base extending from one end to the other, and between the hook and the snap, and the snap being bent at a slight angle, so as to pass over this central wire.

95 My improved button-fastener is employed in the following way: The holes for the reception of the fastener being formed through the leather of the shoe, a fastener is inserted into one of the holes, the hook *a* and snap *c* extending through the hole, and the base *b* fitting 100

against the under surface of the leather. The eye of the button *d* is then pressed against the snap *c* and presses it back, so that the eye enters the hook and is held thereby. It is only necessary that the snap *c* extend up to or slightly above the upper surface of the shoe-leather, as the eye of the button may be pressed down into the leather when entering the hook.

When in use the strain on the button holds 10 the base *b* against the shoe-leather and prevents its pressing against the wearer's foot, and the base gives a strong hold for the button, while the metal wire forms a durable fastener for the button. To remove the button it 15 is only necessary to press back the spring-snap *c*, either on the upper or lower surface of the shoe-leather, and draw the button out of the hook, the button of the shoe being thus changed whenever worn out or for other reason.

20 My invention thus forms a cheap and easily-operated fastener for shoe-buttons, one which can be secured in place without the use of tools for the purpose, and which can be easily operated by the wearer of the shoe.

25 Before my invention a button-fastener has been constructed of a base and an open hook

and arm extending up through the leather, the arm extending beyond the end of the hook, and the eye of the button being pressed downwardly between the hook and arm to enter the 30 fastener. In that fastener, however, if the eye of the button presses against the arm, it is liable to come loose from the fastener, whereas by my invention the button is held in the hook by the snap, and can only be withdrawn when 35 the snap is pressed back.

What I claim as my invention, and desire to secure by Letters Patent, is—

The improved shoe-button fastener herein described, having the base *b*, adapted to fit 40 against the under surface of the shoe-leather, and the hook *a* and spring-snap *c*, adapted to extend through the leather and fit under the hook, and thus hold the button, substantially as described.

45 In testimony whereof I, the said JAMES H. McCCLURE, have hereunto set my hand.

JAMES H. McCCLURE.
